(57) **CLAIM**

The ornamental design for a belt with pockets for holding cooled gel packs, as shown and described.

DESCRIPTION

FIG. 1 is a front elevated view of a belt with pockets for holding cooled gel packs showing my new design.

FIG. 2 is a rear elevated view of the belt with pockets for holding cooled gel packs.

FIG. 3 is a right side elevated view of the belt with pockets for holding cooled gel packs.

FIG. 4 is a left side elevated view of the belt with pockets for holding cooled gel packs.

FIG. 5 is a top plan view of the belt with pockets for holding cooled gel packs; and,

FIG. 6 is a bottom plan view of the belt with pockets for holding cooled gel packs.
